CLAIM

The ornamental design for a plastic bag with textured strips as shown and described.

DESCRIPTION

FIG. 1 is a front elevation of a first embodiment of the invention, the plastic bag having three textured strips, the rear elevation being a mirror image thereof;

FIG. 2 is a bottom plan;

FIG. 3 is a top plan;

FIG. 4 is a right side elevation;

FIG. 5 is a left side elevation;

FIG. 6 is a front elevation of a second embodiment of the invention, the plastic bag having three textured strips, the rear elevation being a mirror image thereof;

FIG. 7 is a front elevation of a third embodiment of the invention, the plastic bag having three textured strips, the rear elevation being a mirror image thereof;

FIG. 8 is a front elevation of a fourth embodiment of the invention, the plastic bag having three textured strips, the rear elevation being a mirror image thereof;

FIG. 9 is a front elevation of a fifth embodiment of the invention, the plastic bag having three textured strips, the rear elevation being a mirror image thereof;

FIG. 10 is a front elevation of a sixth embodiment of the invention, the plastic bag having three textured strips, the rear elevation being a mirror image thereof;

FIG. 11 is a front elevation of a seventh embodiment of the invention, the plastic bag having three textured strips, the rear elevation being a mirror image thereof;

(Continued)

FIG. 12 is a front elevation of an eighth embodiment of the invention, the plastic bag having three textured strips, the rear elevation being a mirror image thereof; and, FIG. 13 is a front elevation of a ninth embodiment of the invention, the plastic bag having three textured strips, the rear elevation being a mirror image thereof.

The shading in FIGS. 1-13 depicts a texture contrast consonant with the visual appearance shown in these drawings. In the figures, a front panel and a rear panel of the plastic bag are transparent, and strips of the plastic bag have stippling to show that they have a different texture, and therefore a texture contrast is depicted between the textured strips and the remainder of the bag.

The top, bottom, left, and right views of the alternative embodiments in FIGS. 6-13 are as shown in FIGS. 2-5. The broken lines define the bounds of the claimed design and form no part thereof.

1 Claim, 12 Drawing Sheets

Related U.S. Application Data

division of application No. 29/466,591, filed on Sep. 10, 2013, now Pat. No. Des. 824,780.
